EMBALMER'S COSMETIC WAX DISPENSING
INSTRUMENT

Marlin R. Henson, Newton, Kans.

Application October 25, 1951, Serial No. 253,061

4 Claims. (Cl. 222—327)

1

The present invention relates to certain new and useful improvements in instruments for containing and forcibly dispensing semi-solid materials or preparations and has more particular reference to what may be called an art pencil, that is, a simple and practical instrumentality which, though usable in other lines of endeavor, is expressly adapted for use in connection with post mortem cosmetology practices.

Classified more specifically, the invention has to do with a novel instrument or so-called art pencil expressly adapted for use as part of the equipment of an embalmer or other licensed person having occasion to practice the requirements of post mortem cosmetology and the restorative arts, this because the instrument contains and aptly dispenses a fine thread of semi-solid cosmetic wax and promotes handy and reliable application of the same to regions of the face, the lips and eyelids, for example, ordinarily difficult to cope with.

Quite often, a day or two after embalming a cadaver, there may be a parting of the eyelids and the lips because of dehydration, post mortem examinations and other post mortem conditions. This instrument will dispense just the proper amount of wax to such opened areas and it is then a simple matter to form the wax with a lip brush or modeling instrument to the natural contours of the lips and eyelids. This instrument is of great value to the embalmer in dispensing the proper amount of wax to surface areas after major features have been rebuilt with a spatula and heavy wax in accidental cases and those that require major restorative work. It will dispense its wax to the rough edges and waves in the surface that result from the spatula and will enable the embalmer to brush the wax out in these areas for an even natural surface. This instrument is of great value in creating wrinkles in the eyelids, especially if tissue has been removed in post mortem derma-surgery. In doing delicate restorative work, the proper technique in using a spatula, which at the present time is the accepted method of applying post mortem wax, is very difficult to master and all students and most licensed embalmers who do not have frequent occasion to do this type of art have difficulty in getting the wax where they need and want it. This instrument will allow them to put the wax where they want and need it and then it is a simple matter to smooth it into the proper contour by the use of a small lip brush or modeling instrument.

Post mortem cosmetic wax at the present time

is packaged in small cans or jars and is in a solid state. It must be taken out of the can or jar with a spatula and worked in the operator's hand with a spatula to obtain a proper consistency. Sometimes it is necessary to add cream to obtain this consistency. It is then applied to the affected area with a spatula. This process requires much time and skill and as a result many cosmetic defects that should and could be corrected easily are permitted to slip by.

A general objective of the invention is to provide an instrumentality having the stated facilities, one which is structurally distinct, unique in its mode of handling and wax application and in which manufacturers and users will find their essential requirements and needs fully met and effectually available.

A further and more specific object is to provide an instrumentality as stated which is characterized by a barrel, axially bored material dispensing head means mounted on the discharge end of the barrel, said head means having finger-accommodating grips or equivalent shoulders providing retention surfaces for the index and middle finger, a material container which is located in the barrel and is in communication with the bore in the head means, and manually actuatable or manipulable force-feed means which is thumb controlled and carried by the barrel and includes a plunger reciprocable in said container for forcibly ejecting the material from the container and dispensing the same by way of the head means, the thumb control means being adjacent to the head means so that the device functions like a miniature force-feed dispensing gun. More specifically, novelty is predicated on a force-feed dispensing device which is characterized by a barrel having means at its discharge end for dispensing material of a predetermined kind, said barrel having a keyway adjacent to said means, a material containing cylinder mounted axially in said barrel, a piston operable in said cylinder, a reciprocable rod operatively connected at one end to said piston, a friction-clutching washer encircling a portion of said rod, a manually actuatable thumb-piece having a key slidably keyed in said keyway, an operating member in said barrel secured at one end to said thumb-piece and hingedly connected at its opposite end to said washer for canting the latter into friction-clutching relation with said rod.

Then, too, it is an object of the invention to provide, as a new article of manufacture, an insertable and removable cartridge comprising an elongated cylinder open and screw-threaded

at one end, the other end having an inturned lateral annular piston-accommodating and retaining flange, a piston arranged in the last-named end portion and abutting said flange, said piston having a rod connecting socket, and a charge of dispensable material packed and filling said cylinder and retaining said piston in place.

Other objects and advantages will become more readily apparent from the following description and the accompanying sheet of illustrative drawings.

In the accompanying sheet of drawings, wherein like numerals are employed to designate like parts throughout the views:

Figure 1 is an elevational view of an art pencil or embalmer's special instrument constructed in accordance with the principles of the present invention.

Figure 2 is a central longitudinal sectional view, on a larger scale, taken on the line 2—2 of Figure 1, looking in the direction of the arrows.

Figures 3 and 4 are cross sections on the lines 3—3 and 4—4 respectively of Figure 2, looking in the direction of the arrows.

Figure 5 is a detail, in section, of the insertable and removable wax-containing cartridge.

Figure 6 is a view showing the ball and socket or flexible connection between the piston and its operating rod.

Referring now to the drawings by reference numerals and accompanying lead lines, the barrel, which is cylindrical, is denoted by the numeral 8. It has a reduced shouldered end portion 10 at its upper end (see Figure 2) and the lower end is internally screw-threaded as at 12. Adjacent this end, the barrel is provided with an elongated slot 14 providing a keyway.

Head means is detachably connected to the screw-threaded end and the latter is denoted generally by the numeral 16 and comprises a suitably shaped and tapering fitting 18 having a central bore and having a screw-threaded neck 20 which is screwed into the screw-threaded end of the barrel, thus plugging this end of the barrel. The opposite end of the fitting is formed with a screw-threaded socket 22 to accommodate an applicable and removable nib 24. The nibs and fittings will be of varying shapes and sizes, so that it is possible to dispense wax in a curved and a straight line or in a curvate line as desired. The fitting is provided with finger-gripping means which here takes the form of diametrically opposite finger recesses or notches 26—26 and attending gripping shoulders 28—28. The cartridge unit is denoted by the numeral 30 and comprises an elongated cylinder 32 having a screw-threaded end 34 detachably coupled with the neck 20. The wax or other material to be dispensed is in the cylinder and this is denoted by the numeral 36. The wax is ejected by a plunger head or piston 38 to which a reciprocating rod 40 is connected. The connection is in the form of a ball and socket joint, as at 42. If desired, there may be a head 44 on the upper end of the rod.

The remote-controlled, thumb-actuated operating means comprises a trigger or so-called thumb piece 46 and this has a body portion 48 which is externally disposed and has a lateral thumb rest 50. There is a key 52 which is slideable in the keyway 14. The part 46 is joined by fastenings 54 with a transversely curved, elongated operating member 56 which is reciprocable in the barrel. This has a hinged connection at 58 at its upper end with a friction clutch washer 60

which surrounds the rod. This friction clutch washer may be drilled at a slight angle—in some cases it allows a better grip and also aids in the return of the washer for a new grip on the rod.

5 There is a second fixed washer 62 carried by the member and it is in spaced parallelism with the washer 60 and also a third washer 64 resting atop the cylinder 32. The rod 40 extends through all three washers 64, 62 and 60, respectively. There 10 is a coil return spring 66 interposed between washers 62 and 60 and a second coil spring 65, which encircles the rod, is interposed between washers 64 and 62. Spring 66 obviously exerts an upward tension on the pivoted or hinged washer 60 so that it will be properly canted in an oblique position to provide the desired friction grip and exert downward pull on the rod 40, to thus operate the piston in the cylinder 32, whereby to forcibly eject the wax or other contents 36 through the head means 16.

In the modification shown in Figure 5, the cartridge 68 comprises a cylinder 70 with an inturned flange 72 at one end and an externally screw-threaded portion at the opposite end, as at 74.

25 The numeral 16 denotes the wax or charge of material which is packed in and fills the cylinder. This serves to hold in place the piston 18 and retains the same against the stop flange 72. The piston is provided with an axial socket 80 to 30 accommodate a ball connecting head on the operating rod. The idea here is that the manufacturer prepares and sells the cartridge 68 in the form shown and including the piston as an element thereof with the wax holding the piston against displacement. Thus, in practice, the used cartridge is removed and the new one shown at 88 is substituted therefor. It is believed that in 35 actual practice the ball and socket connection between the piston and rod may be a snap-joint connection and the showing and description is to be 40 so interpreted.

In operation, it is obvious that by catching hold of the shoulders 28—28 and placing the index and middle fingers in the recesses for convenience, the head means may be properly held and aimed. Then, by exerting downward pressure on the thumb-piece 50 it is obvious that the force-feed means comes into play to eject the wax in a desired manner. The spring 66 exerts tension on washer 60, but, as soon as the operating member 56 is moved, the washer 60 is tilted or canted to provide a friction grip on the rod 40 and to then force the rod downward. The spring 65 returns the thumb-actuated operating means characterized primarily by the friction washer 60, operating member 56 and thumb rest 50. When the thumb pressure is released on the thumb rest 50, the operating means moves upward and washer 60 with the additional help of spring 66 and its suitably angled hole raises on rod 40. The rod and piston are left where they are depending on how much wax is left in the cylinder, as is obvious. It will be clear, then, that the plunger or rod does not move upward when the thumb pressure is released. The friction washer 60, operating member 56, and thumb rest 50 move upward, the friction washer 60 moving upward on and in relation to the then relatively stationary rod 40.

70 In practice, a suitable tubular sheath 82 is provided and is separably joined to the barrel at 84. This provides a proper shield for the parts in the manner shown.

75 It is also to be pointed out that because of the hinge 58 on the friction washer, it may be essen-

tial to drill the hole a little off-center in respect to the somewhat corresponding holes in washers 62 and 64, this so that the tubular sheath will fit properly over the associated parts.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and within the scope of the appended claims.

Having described the invention, what is claimed as new is:

1. A material containing and dispensing device comprising a barrel having means at its discharge end for dispensing material of a predetermined kind, said barrel having a keyway adjacent said means, a material containing cylinder mounted axially in said barrel, a piston operable in said cylinder, a reciprocable rod operatively connected at one end to said piston, a friction-clutching washer encircling a portion of said rod, a manually actuatable thumb-piece having a key slidably keyed in said keyway, an operating member in said barrel secured at one end to said thumb-piece and hingedly connected at its opposite end to said washer for canting the latter into friction-clutching relation with said rod, and a ball and socket connection between said rod and piston.

2. A material containing and dispensing device comprising a barrel having means at its discharge end for dispensing material of a predetermined kind, said barrel having a keyway adjacent said means, a material containing cylinder mounted axially in said barrel, a piston operable in said cylinder, a reciprocable rod operatively connected at one end to said piston, a friction-clutching washer encircling a portion of said rod, a manually actuatable thumb-piece having a key slidably keyed in said keyway, an operating member in said barrel secured at one end to said thumb-piece and hingedly connected at its opposite end to said washer for canting the latter into friction-clutching relation with said rod, a second washer resting atop said cylinder, a third washer fixed to and extending at right angles from said operating member, said washers being in alignment with each other and said rod operating therethrough, a first coil spring surrounding said rod and interposed between said second and third washers, a second coil spring also surrounding said rod and interposed between said first and second-named washers, and a sheath carried by said barrel and enclosing said washers, springs and portions of said rod and operating member.

3. An embalmer's cosmetic wax dispensing pencil useful in post mortem cosmetology practices comprising a linearly straight elongate barrel open and internally screw threaded at its forward end and provided in one side adjacent said forward end with a slot providing a keyway, head means embodying a fitting having a neck screw

threaded and screwed into the cooperating end of said barrel, said neck being internally screw threaded, said head means having finger retaining shoulder means and finger accommodating recess means, a readily applicable and removable elongated cylinder open and screw threaded at one end, the screw threaded end of said cylinder being screwed into the internal screw threads of the stated neck, a piston mounted for reciprocation in said cylinder, said piston having a rod with one end operatively connected to the piston, an externally disposed manually actuatable thumb-piece having a key slidably keyed in said slot, an operating member on the interior of the barrel and interposed between the barrel and the cylinder and having one end connected with said thumb-piece, the opposite end projecting beyond the adjacent end of said cylinder and being opposed in spaced parallelism to said rod, a friction-clutching washer encircling a portion of said rod and hingedly joined to an adjacent end portion of said operating member, and spring means surrounding the rod and interposed between the cylinder and said washer.

4. An embalmer's cosmetic wax dispensing pencil useful in post mortem cosmetology practices comprising a barrel having means at its discharge end for dispensing material of a predetermined kind, said barrel having a keyway adjacent said means, a material containing cylinder arranged axially in said barrel and having one end detachably joined with said dispensing means, a piston operable in said cylinder, a reciprocable rod operatively connected at one end to said piston and having its opposite end projecting beyond the cylinder and barrel, a manually actuatable thumb-piece having a key slidably mounted in said keyway, an elongated transversely curved operating member interposed between said cylinder and barrel and having one end joined with said key and the opposite end projecting well beyond the corresponding end of said cylinder and paralleling said piston rod, a friction-clutching washer encircling a portion of said rod and hingedly attached to an adjacent free end portion of said operating member, and spring means encircling said rod and cooperating with said washer.
